UNITED STATES PATENT OFFICE.

PHILIP W. HUSSEY, OF NORTH BERWICK, MAINE.

AMUSEMENT DEVICE.

Application filed June 25, 1925. Serial No. 39,569.

This invention relates to amusement devices such as are commonly used at swimming pools, bathing beaches, play grounds, amusement parks and the like, and wherein an inclined sliding board or chute is provided down which persons slide for amusement purposes.

The primary object of the invention is to provide a sliding board or chute of the above character with means for launching the user onto the upper end of the board or chute so that the amusement device may be used with greater facility and ease.

Another object of the invention is to provide a launching device of the above character which is extremely simple and durable in construction as well as efficient in operation.

Still another object is to provide a launching device under convenient control of the user.

A further object is to provide an improved structure for supporting the inclined board or chute and a ladder by means of which persons using the device may readily gain access to the upper end of the board or chute.

A still further object is to provide an improved form of raft or floating platform for supporting the amusement device proper upon the water when used at swimming pools, bathing beaches and the like.

With the above general objects in view and others that will become apparent as the nature of the invention is better understood, the same consists in the novel form, combination and arrangement of parts hereinafter more fully described, shown in the accompanying drawings and claimed.

In the drawings, wherein like reference characters indicate corresponding parts throughout the several views,

Figure 1 is a side elevational view of an amusement device constructed in accordance with the present invention and embodying a raft or floating platform,

Figure 2 is a rear elevational view of the lower portion of the device shown in Figure 1 drawn on a larger scale,

Figure 3 is a view similar to Figure 2 of the upper portion of the device shown in Figure 1,

Figure 4 is a top plan view of the device shown in Figure 3,

Figure 5 is a side elevational view of the device shown in Figure 3,

Figure 6 is a top plan view of the portion of the device shown in Figure 2,

Figure 7 is an enlarged perspective view of a detail of the launching device,

Figure 8 is a view similar to Figure 7 of a further detail of the launching device, and

Figure 9 is a vertical sectional view taken substantially upon line 9—9 of Figure 4 to more clearly show further details of the launching device.

Referring more in detail to the drawings, the form of the invention herein shown embodies a chute 5 of conventional form supported in an inclined position by means of forward relatively short supporting legs 6 which are rigidly connected at their upper ends by a transverse member 7 as shown in Figure 2 upon which the lower end of the chute 5 rests and to which it is secured. The legs 6 are braced against separating strains by means of inclined cross braces 8, and further braces 9 have their upper forward ends attached to the upper ends of the legs 6 so as to brace the latter against forward tilting movement. The rear upper end of the chute 5 is supported by means of relatively long rear supporting legs 10 which extend at a slight inclination rearwardly from the upper end of the chute 5 and have their upper ends rigidly attached to the latter as at 11. The rear legs 10 are also connected and braced by means of inclined cross braces 12, and the intermediate portion of the chute 5 is braced and supported by means of forwardly extending bars 13 which are arranged substantially horizontally with their forward ends respectively secured to the ends of a transverse cleat 14 secured to the under side of the chute 5 as clearly shown in Figures 1 and 2, the rear ends of the bars 13 being attached as at 15 to the intermediate portions of the relatively long rear legs 10. The lower ends of the legs 6 and 10 as well as the braces 9 are secured to the floor or supporting platform 16; and it will thus be seen that the chute 5 is effectively supported in a simple and durable manner and in proper position for use.

In the form of the invention shown, the floor 16 constitutes the platform or floor

105

of a raft or floating platform and is composed of a series of transversely extending boards secured upon spaced longitudinally extending pairs of horizontal beams 17 to 5 the sides of which are fastened a plurality of series of transversely aligned saddles or saddle blocks 18 which have concave lower edges in which the upper portions of transversely extending cylindrical floats or buoyant members 19 are seated. The buoyant members 19 are held in the seats of the saddles 18 by means of clamping bands or rings 20 whose ends are secured as at 21 to the ends of the saddles 18 as shown clearly 10 in Figures 1 and 2. A simple and durable form of floating platform or raft is thus provided for supporting the chute 5 on the surface of the water when used for diving and other purposes at swimming pools, 15 bathing beaches or the like.

A ladder 22 is vertically disposed at the rear of the legs 10 for facilitating access to the upper end of the chute 5, and as shown, this ladder extends below the floor 25 or platform 16 so that the user may more readily gain access thereto when the device is used on the water, the lower end portion of the ladder 22 being secured to the platform 16 by means of brace rods 23, while the 30 upper end of the ladder is connected with the upper end of the chute 5 by means of horizontal forwardly projecting arms 24 upon which are secured a plurality of boards forming a platform 25 between the upper 35 end of the chute 5 and the upper end of the ladder 22 as shown clearly in Figure 1. Suitable U-shaped and inverted rails 26 have their ends attached to the ladder 22 and the arms 24 at opposite sides of the 40 platform 25, and these rails provide hand grips to be grasped by the user for insuring safe passage from the upper end of the ladder to the upper end of the chute.

An important feature of the invention is 45 a device for initially supporting the user of the chute 5 and then operable to launch the user of the same into the chute 5. This launching device may be of any preferred form or construction but is herein shown as 50 embodying a seat board 27 to the rear end of which is attached a pair of hinge members 28 which are preferably of substantially Z-shape as shown more clearly in Figures 8 and 9 and which have their upper 55 ends formed with horizontal bearing sleeves 29 that are loosely journaled upon a transverse supporting rod 30 whose ends pass through transversely aligned openings in the upper ends of the sides of the chute 5 and 60 which is suitably held in place in spaced relation to and above the bottom of the chute as shown clearly in Figure 9. The seat board 27 is considerably narrower than the chute 5 as best shown in Figure 4, and the hinge members 28 extend upwardly and

rearwardly from the rear corners of the seat board 27 so that spaces are left between the outer ends of the bearing sleeves 29 of said hinge members and the inner surfaces of the side walls of the chute 5. Encircling 70 the rod 30 between the side walls of the chute 5 and the adjacent ends of the bearing sleeves 29 are helical springs 31, the outer ends of which are secured to the side walls of the chute, and the inner ends of 75 which are suitably attached to the hinge members 28 or the bearing sleeves 29 thereof with the springs under torsional tension so that the seat board 27 is yieldingly held in raised horizontal position as shown in 80 the several views. A transverse shaft 32 is journaled at its ends in brackets 33 to the under side of the central portion of the seat board 27, and rigid with and depending from the central portion of the shaft 32 is a 85 supporting arm 34 having a laterally directed lower end portion 35 adapted to rest upon a transverse supporting roller 36 for positively supporting the seat board 27 in its normal horizontal position. The arm 34 is rigid with the shaft 32, and the laterally directed portion 35 projects rearwardly of the chute and terminates in a depending rearwardly inclined arm or end portion 37 having a rearwardly projecting rigid stop 90 pin 38 on the lower portion thereof. The roller 36 is journaled in suitable bearings attached to the under side of the bottom of the chute 5 and is disposed in line with an opening through the bottom wall of said chute through which the arm 34 is slid able. The roller 36 is disposed in a vertical plane rearwardly of the vertical plane in which the shaft 32 is disposed so that the arm 34 is disposed at a rearward inclination for insuring its automatic forward swinging movement when the seat board 27 is raised by the springs 31 so as to insure positioning of the laterally directed portion 35 upon the supporting roller 36. The stop pin 38 100 is arranged to engage the bottom of the chute 5 for preventing excessive upward movement of the seat board 27, and disposed about the upper end portion of the supporting arm 34 is a helical compression 105 spring 39 whose lower end is adapted to strike the bottom wall of the chute 5 when the seat board 27 is allowed to swing downwardly for launching the user into the upper end of the chute, thereby absorbing any 110 shocks. The spring 39 is suitably attached to the upper end of the arm 34 or to the shaft 32 so as to be maintained in the position shown in Figure 9.

Means is provided for swinging the arm 125 34 rearwardly so as to disengage the offset or laterally directed portion 35 thereof from the roller 36 and to position the upper portion of the arm 34 rearwardly of the roller 36 whereby said arm 34 may slide down- 130

wardly past the roller 36 for allowing the seat board 27 to lower and thereby causing launching of the user into the chute. This means is preferably of a character so as to be under control of the occupant of the seat board 27 and is shown as comprising a transversely extending lever 40 which is pivoted intermediate its ends upon the floor or bottom wall of the chute 5 and has its inner 5 end disposed at the forward side of the arm 34, the outer portion of the lever 40 projecting outwardly through a slot 41 in one side wall of the chute 5 and having its outer end attached to a flexible member or rope 42 10 which extends forwardly and downwardly around a guide pulley 43 suspended from the adjacent side of the chute 5. The rope 42 extends from the pulley 43 rearwardly and upwardly where its other end is attached to 15 an eye 44 carried by the adjacent side of the chute 5 near the seat board 27. It will thus be seen that when the end portion of the rope 42 which is attached to the eye 44 is pulled by the occupant of the seat board 27, 20 the lever 40 will be swung so as to cause the inner end portion thereof to move rearwardly in engagement with the arm 34 for rearwardly swinging the latter until the laterally directed portion 35 leaves the roller 36 whereupon the seat board is free to lower 25 under the weight of the occupant thereof for causing sudden launching of the occupant of the seat board into the chute. This operation is insured as the springs 31 are only 30 of sufficient strength to swing the seat board 27 upwardly and are not of sufficient strength to resist the downward pressure exerted by the weight of the occupant of the seat board when the supporting arm 34 is 35 released.

From the foregoing description it is believed that the construction and operation as well as the advantages of the present invention will be readily understood and appreciated by those skilled in the art.

Minor changes may be made without departing from the spirit and scope of the invention as claimed.

What I claim as new is:

50 1. An amusement device including an inclined sliding board, a trip device, a support pivoted on the upper end portion of said sliding board and adapted to be moved to a horizontal position and to be releasably maintained in such position by said trip device, means adapted to be actuated by the occupant of the support for disengaging the trip device, said support being tilttable by the weight of the occupant thereof upon release of the trip device for launching the occupant onto the sliding board, and yieldable means acting to normally raise the support for automatically returning the latter to a horizontal position after the occupant 55 is launched therefrom.

2. An amusement device including an inclined sliding board, a trip device, a support pivoted on the upper end portion of said sliding board and adapted to be moved to a horizontal position and to be releasably maintained in such position by said trip device, means adapted to be actuated by the occupant of the support for disengaging the trip device, said support being tilttable by the weight of the occupant thereof upon release of the trip device for launching the occupant onto the sliding board, and yieldable means acting to normally raise the support for automatically returning the latter to a horizontal position after the occupant is launched therefrom; said trip device being automatically settable for releasably maintaining the support horizontally positioned when returned to such position by said yieldable means.

3. An amusement device including an inclined sliding board, a trip device, a support pivoted on the upper end portion of said sliding board and adapted to be moved to a horizontal position and to be releasably maintained in such position by said trip device, and means adapted to be actuated by the occupant of the support for disengaging the trip device, said support being tilttable by the weight of the occupant thereof upon release of the trip device for launching the occupant onto the sliding board, said trip device including a trip arm hinged at its upper end to the support and adapted for supporting engagement with the sliding board.

4. An amusement device including an inclined sliding board, a trip device, a support pivoted on the upper end portion of said sliding board and adapted to be moved to a horizontal position and to be releasably maintained in such position by said trip device, and means adapted to be actuated by the occupant of the support for disengaging the trip device, said support being tilttable by the weight of the occupant thereof upon release of the trip device for launching the occupant onto the sliding board, said trip device including a vertically swinging trip arm hinged to and depending from the support.

5. An amusement device including an inclined sliding board, a trip device, a support pivoted on the upper end portion of said sliding board and adapted to be moved to a horizontal position and to be releasably maintained in such position by said trip device, means adapted to be actuated by the occupant of the support for disengaging the trip device, said support being tilttable by the weight of the occupant thereof upon release of the trip device for launching the occupant onto the sliding board, said trip device including a vertically swinging trip arm hinged to and depending from

the support, and said trip device disengaging means including a horizontal actuating lever for the trip arm projecting outwardly beyond one side of the sliding board beneath the support.

6. An amusement device including an inclined sliding board, a trip device, a support pivoted on the upper end portion of said sliding board and adapted to be moved to a horizontal position and to be releasably maintained in such position by said trip device, means adapted to be actuated by the occupant of the support for disengaging the trip device, said support being tiltable by the weight of the occupant thereof upon release of the trip device for launching the occupant onto the sliding board, said trip device including a vertically swinging trip arm hinged to and depending from the support, and a supporting element carried by the sliding board, said trip arm being slidable through the sliding board rearwardly of its point of attachment to the support, and means to automatically move the trip arm forwardly into engagement with the supporting element when the support is raised.

7. An amusement device including an inclined sliding board, a trip device, a support pivoted on the upper end portion of said sliding board and adapted to be moved

to a horizontal position and to be releasably maintained in such position by said trip device, means adapted to be actuated by the occupant of the support for disengaging the trip device, said support being tiltable by the weight of the occupant thereof upon release of the trip device for launching the occupant onto the sliding board, said trip device including a vertically swinging trip arm hinged to and depending from the support, and a cushion element on the upper end of the trip arm for absorbing shock incident to tilting of the support.

8. An amusement device including an inclined sliding board, a trip device, a support pivoted on the upper end portion of said sliding board adapted to be moved to a horizontal position and to be releasably maintained in such position by said trip device, and means adapted to be actuated for disengaging the trip device, said support being tiltable by the weight of the occupant thereof upon release of the trip device for launching the occupant onto the sliding board, and yieldable means acting to normally raise the support for automatically returning the latter to a horizontal position after the occupant is launched therefrom.

In testimony whereof I affix my signature.
PHILIP W. HUSSEY.
